UNITED STATES PATENT OFFICE

CHARLES H. WINDSOR, OF PALMYRA, NEW JERSEY

SANITARY BASIN

Application filed October 11, 1928. Serial No. 311,790.

The present invention relates to receptacles and more particularly to a washing receptacle, such as a sanitary wash basin, formed from paper or similar material and to an improved support therefor.

The use in hotels, public, and semi-public places of the same wash bowl by a large number of persons, is frequently the cause of the spread of skin and other diseases. Travelers have often experienced annoyance and discomfort because it is necessary to use a basin previously used by others and which obviously has not been thoroughly cleansed. Moreover, in many States, laws have been enacted forbidding the use in trains, public comfort stations, and the like, of the same basin by more than one person. In my Patent 1,538,016, granted May 19, 1925, there is shown a sanitary wash basin adapted for use with a suitable support adapted to clamp its margin as disclosed therein, a support of this type being disclosed in my Patent 1,499,495, granted July 1, 1924.

An object of the present invention is to provide a sanitary wash basin which, after use, may be discarded but which, if desirable, may be repeatedly used by the same person.

A further object of the invention is to provide a paper receptacle adapted for such use and which has a margin suitably stiffened to serve as a support for the receptacle when filled. The invention also contemplates the provision of a marginal stiffening means which serves to fasten permanently the ends of the pleat or pleats which open up inwardly from the margin to provide the necessary concaved or dished formation.

Another object of the invention is to provide a fixture or basin having a bowl in which are arranged suitable rests or shelves for the supporting margin of the paper receptacle. The invention seeks to provide a rest which will sustain the filled receptacle below the top of the bowl and with the margin of the receptacle intermediate the rests spaced inwardly from the bowl wall whereby overflow from the receptacle may pass downwardly into the bowl to a drain therefrom.

The invention also contemplates the pro-

vision of rests for the receptacle margin the rests or supports being in a vertical plane offset from the bowl wall, preferably projecting into the bowl area, and of a character which will support the receptacle in such a way that a portion thereof is disposed beneath the inlet spout or spouts of the basin. For this purpose the rests are preferably arranged in a horizontal plane below the mouth of the spout or spouts. Moreover, the rests are preferably disposed at the ends of the bowl and of sufficient width to engage a basin throughout the greater portion of the width of the basin whereby to prevent tilting movement. If desired, the rests may be formed so as to engage the basin in such a way as to prevent turning or sliding movement of the same.

The foregoing and other objects of the invention, which are more closely related to details of construction, will be made clearer as the description proceeds in connection with certain preferred embodiments shown in the accompanying drawings wherein

Figure 1 is a top plan view of a receptacle blank.

Figure 2 is a sectional view on the line 2—2 of Figure 1.

Figure 3 is a sectional view on the line 3—3 of Figure 1.

Figure 4 is a fragmentary sectional view.

Figure 5 is a fragmentary sectional view.

Figure 6 is a vertical sectional view showing the receptacle supported within a bowl of improved construction.

Figure 7 is a top plan view of the combination illustrated in Figure 1.

Figure 8 is an enlarged detail view of the supporting surfaces of one of the rests within the bowl.

Figure 9 is a top plan view of a bowl provided with supports or rests of modified construction, and

Figure 10 is a plan view of a receptacle blank of somewhat modified construction.

Referring to the drawings for a more detailed description, the receptacle or collapsible basin may be formed of any suitable material such as relatively thin parchmentized paper adapted to withstand water and which

is comparatively inexpensive, so that the basin may be discarded after it has been used once. The drawings illustrate the hand basin or wash bowl type and the article shown is formed from a blank 10 of elliptical contour. The blank has a transversely extending fold or pleat 11 which is preferably continuous from edge to edge of the blank. The pleat in the present instance coincides with the major axis of the ellipse defined by the contour of the blank and is formed so that when pressure is applied to the blank while the same is supported along its margin, the pleat will open, permitting the central portion of the blank to be depressed, and thereby forming a dish-like receptacle.

The provision of a single pleat which opens freely will form a suitable receptacle. However, in the preferred embodiment of the invention, shown in the drawings, an additional pleat is provided. The additional pleat or fold 12 extends transversely of the blank at an angle to the first mentioned pleat which it intersects, preferably at substantially the center 13 of the blank. This pleat 12 coincides with the minor axis of the ellipse defined by the contour of the blank and at the point of intersection of the pleats is formed by folding over upon itself a portion of the pleat 11, as indicated in Figure 2.

It will be noted that both pleats are of substantially uniform width from edge to edge of the blank, which is desirable, although not necessary, and that the pleats are continuous, their ends being at the margin of the blank.

The structure thus far described is similar to that disclosed in my patent above mentioned. However, it will be noted that the margin of the blank is not bent, but is disposed in substantially the same plane with the remainder of the blank before the same is depressed by opening the pleats. The present invention contemplates the treatment of the blank margin in such a way that the ends of the pleats are permanently fastened in the formation of the blank, whereby it is not necessary to employ a support adapted to retain the ends of the pleats against opening when the remainder of the pleats are opened to depress the bowl inwardly from its margin. Moreover, the invention contemplates a fastening means for the pleat ends which will impart stiffness to the margin of the blank for a distance sufficient to enable the margin when rested upon a support, to sustain the filled receptacle, thus eliminating the necessity for using a support which clamps the margin of the blank.

Any suitable pleat-fastening and margin-stiffening means may be employed. For example the embodiment of the invention illustrated includes a channel element 13' which receives the edge of the blank at the ends of the pleats and is adapted to hold the ends of the pleats against opening when the blank

inwardly from its margin is depressed. If desired, the bottom web of the channel element 13' may be somewhat wider than the top web (Fig. 4) and may terminate in a downwardly curled edge 13'', which provides a rounded portion for engagement with the paper of the basin when the latter is flexed downwardly as indicated in Fig. 6, thereby minimizing the danger of tearing the paper of the basin when filled with water. The channel element may be formed from any suitable metallic or fibrous material, and preferably is extended around the blank from each pleat sufficiently to impart to the margin of the blank suitable stiffness to permit the margin to serve as a support for the receptacle when filled. Although the channel element illustrated extends entirely around the blank, it will be understood that it is simply desirable that the means employed should extend a sufficient distance to impart to the margin the rigidity necessary to support the filled receptacle formed from the blank.

The blank with its means for permanently fastening the ends of the pleat and stiffening the margin to provide a support may be positioned upon any suitable device adapted to provide a rest for the blank margin and to permit the central portion of the blank to be depressed to open those portions of the pleats disposed inwardly from the margin of the blank. When the blank center is depressed, as shown in Figure 6, there is provided a receptacle, the surface of which is smooth and devoid of interstices which would tend to collect sediment and other impurities. The pleats are comparatively loose inwardly from the blank margin so that upon application of the pressure to the central portion of the blank the pleats will open freely throughout substantially their entire length except, of course, immediately adjacent the margin where they are gripped by the channel element.

Obviously, the depth of the basin depends upon the width of the pleats and by forming the pleats of greater or less width the capacity of the basin may be varied. Moreover, the extent and character of the stiffening means may vary in accordance with variation in the size of the receptacle since the weight of the filled receptacle will vary directly in proportion to its size or capacity.

Referring to Figure 10, there is shown a blank of the same general construction as that above described, but provided with a plurality of independent pleat fastening means, such as channels 14, 15, the channels 15 being disposed at the ends of the major axis and being of somewhat greater extent than the other channels since they serve as the sustaining means for the blank when positioned upon a support of the character hereinafter described.

An improved feature of the invention, and

an element of the combination included in the invention, is a support of improved form which cooperates with the receptacle. The receptacle is intended to be inserted within the bowl 16 of a basin 17 having a marginal portion 17' surrounding the top of the bowl and an inlet spout 18 of conventional construction. In the present instance, the spout 18 is of the type formed integral with the bowl although it will be understood that the invention contemplates association of the receptacle with a basin having inlet spouts of other conventional forms, such as the separate faucet spouts.

In vertical planes offset from the bowl wall, and in the present instance projecting into the bowl area at each end of the bowl, is arranged a shelf or rest 19, the rests being confined to substantially the ends of the bowl whereby the inner surfaces of the bowl at the front 16' and rear 16'' thereof are unobstructed. These shelves are adapted to receive the stiffened margin of the receptacle blank, as illustrated in Figure 6, and to support the same so that a portion of the receptacle is disposed beneath the spout 18. For this purpose the shelves, as will be observed, are arranged in a horizontal plane below the outlet or mouth of the spout. Moreover, as is apparent from Figure 7, the supporting bowl is so formed relative to the receptacle and the rests are so arranged within the bowl that the opposite marginal portions 14', 15', of the receptacle intermediate the rest and at the front and rear of the bowl, are spaced inwardly from the bowl wall whereby to provide the spaces 20 through which an overflow from the receptacle may pass downwardly into the bowl and be discharged therefrom from the usual drain opening 21.

As will be observed, the rests or supports, although of less extent than the bowl circumference, are nevertheless of sufficient width to engage the collapsible basin margin throughout the greater portion of the width of the basin, thereby effectively resisting tilting movement and also preventing bending of the basin when filled with water.

When the receptacle is disposed within the bowl with its stiffened margin bearing upon the rests 19 a pressure upon the central portion of the blank will depress and dish the blank by opening the pleats. Thereafter water may be introduced into the receptacle thus formed, through the spout 18 and, as explained, any overflow during the filling of the receptacle, or as the same is used, will pass downwardly into the bowl through spaces 20 at the front and rear of the bowl. In order to resist sliding movement of the receptacle upon the rests 19, the latter and the receptacle margins may be formed with suitable means adapted to interengage. For example, the channel member 13, may be

stamped out to provide tits 24 to project into cups or sockets 25 in the top surfaces of the rests.

Referring to Figure 8, there is shown a bowl 26 having rests 27 slightly different in construction from the rests or shelves illustrated in Figure 6. Each of the rests 27 is formed from a length of metal rod or tubing having a transverse supporting portion 27' and ends 28 bent at an angle thereto and extended into the bowl wall through which they pass and receive outside the bowl securing nuts 29. This type of rest or shelf may be readily applied to bowls wherever it is desired that the shelf shall not be integrally formed with the bowl; for instance, to bowls now in use to support my improved receptacle.

In both forms of the basin shown and described, it will be observed that there are no obstructions above the supports or rests and hence the paper basin or receptacle may be readily deposited on and removed from the supports. The application and removal of the receptacle is facilitated by the spaces intermediate the supports into which the hands may be inserted to engage the paper basin.

Since the receptacle is formed with a stiffened margin which will support the same as described, it is unnecessary to provide a rest which will clamp the margin of the receptacle or hold the pleats against opening. Moreover, since the blank is flat as distinguished from the blank having the angularly deflected margin of my patent, the same may be more conveniently packed in transportation and readily stacked for dispensing.

Furthermore, it will be understood that although the blank shown in the drawing is of elliptical contour, this is not an essential feature of the invention since it may be made round or rectangular, or of any other design.

Where the blank or receptacle is referred to in the claims as a "collapsible basin" it will be understood, of course, that the term is used in a broad sense to cover any receptacle of the sanitary type made from paper, parchment or similar material, and which is intended to be discarded after use.

Obviously, numerous changes may be made in the structures illustrated and described without departing from the invention, the principal features of which are defined in the following claims.

I claim:

1. A basin having a bowl provided with a drain opening in its bottom, a water inlet spout, said bowl having surrounding the same at its top a marginal basin portion and below the said marginal portion at the ends of the bowl substantially opposite supports of less extent than the bowl circumference but of substantial width to engage the ends of a collapsible basin throughout the greater

portion of the basin width and prevent tilting thereof, said supports being offset from the bowl wall and disposed below the plane of the water inlet whereby to suspend a collapsible basin with a portion thereof beneath said inlet and with its edge spaced from the bowl wall intermediate the supports, the basin above said supports being substantially open and unobstructed by said marginal portion whereby a collapsible basin may be readily deposited on and removed from the supports.

2. A basin having a bowl provided with a drain opening in its bottom, a water inlet spout, said bowl having surrounding the same at its top a marginal portion and below the said marginal portion at the ends of the bowl substantially opposite supports of less extent than the bowl circumference, said supports being in vertical planes offset from the bowl wall and disposed below the plane of the water inlet whereby to suspend a collapsible basin with a portion beneath said inlet and with its edge spaced from the bowl wall intermediate the supports, the basin above said supports being substantially open and unobstructed by said marginal portion whereby a collapsible basin may be readily deposited on and removed from the supports, and an imperforate collapsible basin having an outwardly projecting stiffened rim adapted to engage said supports and to be suspended in the bowl thereby with its edge intermediate the supports spaced from the bowl wall, said supports being adapted to engage the basin at its ends throughout the greater portion of the basin width whereby to prevent tilting thereof.

3. A basin having a bowl provided with a drain opening in its bottom, a water inlet spout, said bowl having surrounding the same at its top a marginal basin portion and below the said marginal portion at the ends of the bowl substantially opposite supports of less extent than the bowl circumference but of substantial width to engage the ends of a collapsible basin throughout the greater portion of the basin width and prevent tilting thereof, said supports being offset from the bowl wall and disposed below the plane of the water inlet whereby to suspend a collapsible basin with a portion thereof beneath said inlet and with its edge spaced from the bowl wall intermediate the supports, the basin above said supports being substantially open and unobstructed by said marginal portion whereby a collapsible basin may be readily deposited on and removed from the supports, and said supports being formed to resist sliding movement of a basin resting thereon.

In testimony whereof I have hereunto set my hand.

CHARLES H. WINDSOR.
